UNITED STATES PATENT OFFICE.

ERNEST F. ELMBERG, OF CHICAGO, ILLINOIS.

ATTACHMENT FOR TYPE-WRITING MACHINES.

No. 810,895.

Specification of Letters Patent.

Patented Jan. 23, 1906.

Application filed May 18, 1904. Serial No. 208,497.

To all whom it may concern:

Be it known that I, ERNEST F. ELMBERG, a citizen of the United States, residing at Chicago, in the county of Cook and State of Illinois, have invented a new and useful Attachment for Type-Writing Machines, of which the following is a specification.

This invention relates to attachments for type-writing machines.

10 The object of the invention is to provide an attachment for type-writing machines which is simple in construction and efficient in operation for making duplicate ink copies.

15 A further object of the invention is to provide an attachment for type-writing machines wherein the paper is carried in rolls and fed through the machine and the sheets or portions thereof being severed or cut after the writing operation is completed.

20 A further object of the invention is to provide an attachment for type-writing machines which is simple and efficient, wherein a plurality of ink-ribbons or duplicating-strips are wound upon reels which are suitably actuated 25 automatically to feed or shift such ribbons or strips, the paper being adapted to pass between such ribbons or strips.

25 A further object of the invention is to provide means for supporting, guiding, and feeding the paper through the machine.

30 Other objects of the invention will appear more fully hereinafter.

35 The invention consists, substantially, in the construction, combination, location, and arrangement of parts, all as will be more fully hereinafter set forth, as shown in the accompanying drawings, and finally pointed out in the appended claims.

40 Referring to the accompanying drawings and to the various views and reference-signs appearing thereon, Figure 1 is a view in top plan of the paper-carriage of a type-writing machine, showing the application thereto of an attachment embodying the principles of my invention. Fig. 2 is a view in front elevation of 45 the construction shown in Fig. 1. Fig. 3 is a view in transverse section on the line 3 3 of Fig. 2 looking in the direction of the arrows. Fig. 4 is a broken detail view in section on the line 4 4 of Fig. 1 looking in the direction of the arrows. Fig. 5 is a broken detail view in perspective of a portion of the feed-plate over which the paper is fed to the machine and showing the slot therein for securing lateral 55 adjustment of the side guides. Fig. 6 is a broken detail view, in front elevation, of the

ink or copying ribbon or strip guiding rollers. Fig. 7 is a broken detail view in section on the line 7 7 of Fig. 6 looking in the direction of the arrows. Fig. 8 is a broken detail view in section of the severing knife or cutter. Fig. 9 is a broken detail view showing means for actuating the copying-ribbon reels. Fig. 10 is a view in section of a copying ribbon or strip supporting reel on the line 10 10 of Fig. 11 looking in the direction of the arrows. Fig. 11 is a broken detail view in section on the line 11 11, Fig. 10, looking in the direction of the arrows. Fig. 12 is an enlarged detail view, in transverse section, showing the roller or platen and the relative arrangement of the copying ribbons or strips and the sheets of paper.

The same part is designated by the same reference-sign wherever it occurs throughout the several views.

In the accompanying drawings, reference-sign A designates the carriage of a type-writing machine, which, in the particular form which I have selected for the purposes of illustration, is the ordinary carriage of an Oliver type-writer, although I desire it to be understood that my invention is not to be limited or restricted in its application to any particular style or type or make of type-writing machine. The carriage A is provided with the usual roller or platen B, around the peripheral surface of which the paper is passed, and also with the paper-guide rollers C, arranged in the usual manner. The platen or roller B is 90 provided with the usual extensions or handles D from the ends of the axle thereof, by which said roller or platen may be rotated by hand or otherwise to advance the paper through the machine. Suitably mounted upon the 95 carriage A and extending parallel with the platen or roller B is a supporting-rod E, having the ends thereof extending beyond the ends of the carriage and upturned and bent horizontally at the extreme ends thereof, as indicated at F, Figs. 1 and 3. Upon each of the bent ends F of rod E is mounted a reel G, upon which two or more ink or copying ribbons H are wound, said ribbons or strips being guided from each of the reels between 100 suitably-arranged guide-rollers J and arranged parallel with and adjacent to the peripheral surface of the platen-roller B, between guide-rollers J, on the opposite side of the carriage 105 and to and upon the reel G at the opposite side of the carriage. These ribbons may be secured upon the reels G in any convenient

manner. I have shown a simple arrangement wherein the hub portion of the reels G are provided with pins K, (see Figs. 10 and 11,) having hooked ends over which the extreme ends of the ribbons or strips are hooked or engaged, such ribbons or strips being thereafter reeled upon the reels in the ordinary way. If desired, and in order to prevent too-free rotation or rotary movement of the reels in reeling or shifting the copying strips or ribbons from one reel to the other, a spring tension may be applied to the reels in any convenient manner. I have shown a simple arrangement wherein a spring-plate L is mounted to be adjustably clamped by a thumb-nut M against the faces of the reels. Upon or associated with each reel G is a ratchet wheel or disk N, the teeth of the ratchet wheel or disk N on one side of the machine being presented in a direction opposite to those of the reel on the opposite side of the machine, as shown most clearly in Fig. 2.

O designates a stationary bar of the machine-frame rigidly held and carrying angle-arms P at each end thereof. Each angle-arm P is provided with a pawl Q, arranged to cooperate with the ratchet-disks N to impart a step of rotary movement to the reels G as the paper-carriage is shifted endwise in the ordinary manner to commence each line of the writing, such shifting movement in one direction causing a tooth of one of the ratchet-disks to be brought into engagement with the pawl Q, carried by the stationary angle-arm P on the same side therewith of the machine, and hence, imparting a step of rotary movement to the reel, and similarly when the carriage is shifted or reaches the limit of its movement in the opposite direction the pawl Q on the other angle-arm engages the teeth of the ratchet-disk on the reel on the opposite side of the machine. Since the teeth of these ratchet-wheels are, as above stated, presented in opposite directions, the angle-arms P are reversed in position on opposite sides of the machine, the arm on the left-hand side of the machine, as viewed in Fig. 2, being presented downwardly, as shown, and that on the right-hand side of the machine being presented upwardly. It is not intended that both of these shifting devices for the reels G be brought into operation at the same time, for in such case the ribbons or strips would be shifted one step in one direction and then back again alternately as the paper-carriage was shifted from one side of the machine to the other. It is intended, therefore, that only one of the reels be thus positively and automatically actuated, so as to completely reel the copying ribbons or strips from one reel to the other and then back again, as may be desired. To this end it is desirable to provide means whereby either one or the other only of the reels be rotatively operated at the same time and whereby the feeding or shifting action of

the ribbons or strips may be shifted from one side of the machine or from one reel to the other. To accomplish this result, I provide the engaging pawls Q with an elongated slot R, through which passes a stud S, whereby said pawls are loosely mounted and may be readily shifted or moved endwise or rotatively moved about their studs, and on the angle-arms P adjacent the studs I arrange a stop T, with which the pawls engage. By this construction the pawls Q may be readily shifted into engaging position, as shown to the left of Fig. 2 and in Fig. 9, with reference to the ratchet-wheels N, or said pawls may be shifted or moved out of engaging relation, as indicated in dotted lines at the right of Fig. 2. By this means I am enabled to provide for rotatively actuating either of the reels automatically at each complete excursion of the paper-carriage, and by rotatively operating one of such wheels the ribbons or copying strips are wound thereon and from the other of such reels. It will be observed that this ribbon-feeding operation, while automatic, is entirely independent of the paper-feeding movement of the platen of the machine.

From the reels, as above stated, the copying ribbons or strips pass between guide-rollers, (indicated at J.) These guide-rollers are provided with extensions A' at the ends thereof, which project through the slots B' in side plates C', suitably mounted upon supporting-studs D', carried by the rod or bar E. These guide-rolls are arranged in pairs, one pair at each side of the machine below and adjacent the corresponding ribbon or strip reel, and the ribbons or copying-strips are designed to be passed between each pair of guide-rolls, whereby they are maintained in proper flattened condition and relation, and by arranging the pairs of rolls in substantially the same horizontal plane parallel with and tangential to the upper surface of the roller-platen the copying ribbons or strips are brought into proper relation with respect to the roller-platen to perform their function as copying ribbons or strips. In order to secure a yielding gripping action of the guide-rolls upon the strips or ribbons, a spring-pressure may be applied to such guide-rolls in any convenient manner—as, for instance, by means of springs E', arranged to bear against the projecting pintles A' of the upper member of each pair of such rolls, as clearly indicated in the drawings.

As above indicated, an attachment for type-writers embodying the principles of my invention, while capable of general use in connection with type-writing machines of any desired make, type, or style, is specially designed for use in connection with paper carried in rolls and in a continuous sheet, the continuous sheets being drawn from the rolls and passed through the machine to receive the writing from the manipulation of the type-

writer keys in the ordinary manner and designed to be torn off or severed, according to the desire of the operator, into lengths of any desired extent. Referring to Fig. 3, reference-signs F' G' designate two continuous strips of paper designed to be passed through the machine, being respectively carried in the form of rolls H' J'. These rolls may be supported in any suitable or convenient manner. I have shown a simple arrangement, to which, however, I do not desire to be limited or restricted, wherein I employ standards K', having bayonet-slots L' in one edge thereof adapted to receive the projecting ends or pintles M' of the studs or shafts upon which the paper-rolls H' J' are formed. In this manner the rolls are readily removable and detachable for renewal or replacement. If desired, and in order to lock the paper-rolls in their supporting-standards, pivot-dogs N' may be employed, the same being pivotally mounted upon the standards adjacent the bayonet-slots in the edges thereof and in position to fit over the projecting ends M' of the roll-cores, as clearly shown. While I have shown only two rolls of paper and two copying ribbons or strips, it is obvious that any desired number of such rolls and ribbons or strips may be employed without departure from the spirit or scope of my invention. Where the standards K' are not mounted to move coincidently with the carriage, they should be placed a sufficient distance from the carriage to enable the strips of paper F' G', leading from the rolls H' J' to the carriage, to become sufficiently slack to prevent unduly crumpling of such sheets during the back-and-forth movements of the carriage.

In order to present the continuous strips or bands of paper from the rolls to the machine, I provide suitable guides. Many specifically different forms of guides may be employed, the object and purpose being to properly maintain the strips of paper in flattened condition and to guide the same properly to the platen-roller B and around the same. I therefore do not desire to be limited or restricted to the exact form of guide shown and now to be described. In the particular form shown I employ a platform O', having transverse slots or openings P' therethrough. This platform O', I suitably mount upon the paper-carriage A in any convenient manner and arrange the same to extend preferably in an inclined position rearwardly or toward the supporting-standards K' of the paper-rolls, and I provide suitable side guides Q' upon the upper surface of the platform O' and adjustable toward and from each other in the transverse slots P' to any desired degree, according to the width of the paper. At the extreme outer ends of the side guides Q', I arrange a guide-rod R', underneath which the strips of paper F' G' pass from the rolls H' J' to the machine.

After the strips of paper are passed around

the periphery of the platen-roller B they are so arranged as to receive the copying ribbons or strips between them, as clearly indicated in Fig. 12.

After the writing has been completed it is necessary to provide means whereby the record or writing strips be detached or severed from the continuous web fed through the machine. To this end I provide a severing blade or cutter A², underneath the severing edge of which the strips of record-paper F' G' pass after leaving the roller-platen, whereby by grasping the protruding or projecting ends of the record-sheets F' G' they may be severed from the web and at any desired point as to length thereof.

After the paper has passed the platen-roller B it is desirable to provide means for delivering it or the sheets thereof outwardly and upwardly, so as to prevent such sheets from following down and around the surface of the roller. To accomplish this result, I provide a guide-plate B³, (see Figs. 1 and 3,) said guide-plate being supported upon the rod E and having its front edge arranged to extend parallel with and in close proximity to the peripheral surface of the platen-roller and in position to engage and deflect the front ends of the record sheets or strips upwardly over the same and past the knife-edge of the cutter.

It may sometimes be desirable, especially in initially starting the continuous strips of record-paper through the machine, to provide means whereby the severing-cutter A² may be thrown back out of the way, so as to facilitate the entrance and proper relative adjustment of the strips of record-paper through the machine. To accomplish this result, I provide the ends of the knife-bar A² with sleeves A³, (see Figs. 1, 3, and 8,) fitting over the rod or bar E and constituting, in effect, a hinge-joint connection by which the cutter-bar A² may be swung or rocked backwardly about the rod E as an axis and out of the way whenever it is desired to do so. This cutting-bar may be clamped in position when once adjusted in any convenient manner—as, for instance, by means of the set-screws C³.

As above indicated, an attachment embodying the principles of my invention is adapted for general use in connection with type-writing machines, and the attachment is of such construction that it may be readily applied to type-writing machines of any type or make.

Having now set forth the object and nature of my invention and a construction embodying the principles thereof, what I claim as new and useful and of my own invention, and desire to secure by Letters Patent, is—

1. In a type-writing machine, the combination with a paper-feed carriage, of a rod or bar carried by said carriage and having its ends projecting or extending beyond the ends of said carriage, ribbon-reels mounted to rotate upon the extending ends of said rod or

- bar, and means for rotatively actuating said reels.
2. In a type-writing machine, the combination with a paper-feed carriage, of a rod or bar carried by said carriage and having its ends projecting or extending beyond the ends of said carriage, ribbon-reels mounted to rotate upon the extending ends of said rod or bar, and automatic means for rotatively actuating said reels.
3. In a type-writing machine, the combination with a paper-feed carriage, of a rod or bar carried by said carriage, but incapable of movement relative thereto, said rod or bar having its ends projecting beyond the ends of said carriage, a ribbon-reel mounted to rotate upon each projecting end of said rod or bar, and means for periodically moving said ribbon-reels rotatively.
4. The combination with the paper-carriage of a type-writing machine, of a rod or bar mounted thereon to move therewith and having its ends projecting beyond the ends of said carriage, a ribbon-reel carried by each end of said rod, a ratchet-disk connected to each reel, and stationary arms carrying pawls arranged to engage said ratchet-disks to rotatively actuate said reels.
5. The combination with the paper-carriage of a type-writing machine, of a rod or arm mounted thereon to move therewith and having its ends extending beyond the ends of said carriage, a ribbon-reel supported upon each projecting end of said rod, a ratchet-disk connected to each reel, a stationary arm associated with each reel, and a movable pawl carried by each arm and cooperating with the ratchet-disk of its associated reel.
6. The combination with the paper-feed carriage of a type-writing machine, of a rod mounted upon said carriage to move therewith, a ribbon-reel carried by said rod, a ratchet-disk connected to said reel, a stationary arm, a pawl mounted upon said arm, said pawl having an elongated slot therein, whereby it is movable into and out of engaging relation with respect to said ratchet-disk.
7. The combination with the paper-feed carriage and platen of a type-writing machine, of a rod or bar mounted on said carriage to move therewith, and having its ends projecting beyond the ends of said carriage, a ribbon-reel mounted upon each projecting end of said rod or bar, pins carried by the hub of each reel and arranged to engage the ribbons, and ratchet mechanism independent of the feed movements of the platen for imparting rotary movement to said reel.
8. The combination with the paper-carriage and feed-platen of a type-writing machine, of a rod or bar carried by said carriage and having its ends projecting beyond the ends of said carriage, a ribbon-reel carried by said bar at each end thereof and each provided with means for engaging the ends of the ribbons, detachable ratchet mechanism independent of the feed movements of the platen for imparting rotation to either of said reels at will, and means for applying a tension to resist the rotative movement of such reels.
9. The combination with the paper-feed carriage of a type-writing machine, a rod or bar carried thereby and having its ends projecting beyond the ends of said carriage, a ribbon-reel mounted on each end of said rod or bar, a ratchet connected to each reel, the ratchets having their teeth presented in opposite directions, and detachable pawls respectively cooperating with said ratchet-disks, whereby the ribbons may be automatically reeled from either of said reels and coiled upon the other.
10. The combination with the paper-feed carriage and platen of a type-writing machine, of ribbon-reels mounted on said carriage to move therewith, and means independent of the feed movements of the platen for automatically actuating said reels to unwind the ribbon from one reel and to wind the same upon the other reel.
11. In an attachment for type-writing machines employing a paper-feed carriage, the combination with a reel carrying a continuous record-strip to be fed to said carriage and means for supporting said reel, of ribbon-supporting devices mounted on said carriage and arranged to support a ribbon in position for the continuous record-strip to pass between the same and the carriage-platen, means for actuating said ribbon-supporting devices to shift the ribbon, and a severing blade or cutter, mounted upon the carriage adjacent the ribbon and transverse to the line of feed of the continuous record-strip.
12. The combination with the paper-feed carriage of a type-writing machine, including a roller-platen, of ribbon-reels mounted on said carriage to move therewith, guide-rollers arranged in pairs at the opposite ends of said platen-roller and in a plane substantially tangential to the surface of the roller, the ribbons passing from one reel between the members of said pairs of guide-rollers to the other of said reels, and means for automatically rotating either of said reels.
13. In an attachment for type-writing machines employing a paper-feed carriage, the combination with a rod or bar mounted on the carriage and having its ends extending beyond the ends of the carriage of ribbon-reels mounted to rotate upon the extending ends of said rod or bar, means for rotatively actuating said reels to shift the ribbon and a record-sheet-deflector plate mounted on said rod or bar and arranged to deflect the record-sheet away from the carriage after passing the ribbon.
14. In an attachment for type-writing machines employing a paper-feed carriage, the combination with a rod or bar mounted on the

- carriage and having its ends extending beyond the ends of the carriage, of ribbon-reels mounted to rotate upon the extending ends of said rod or bar and a severing-blade also 5 mounted upon said rod or bar in position to sever the record-strip after it has passed the ribbon.
15. In an attachment for type-writing machines employing a paper-feed carriage, the 10 combination with a rod or bar mounted upon the carriage and having its ends extending beyond the ends of the carriage, of ribbon-reels mounted to rotate upon the extending ends of the rod or bar, means for rotatively 15 actuating the ribbon-reels to shift the ribbon and a severing-blade adjustably mounted upon said rod or bar and arranged in position to sever the record-strip after it has passed the ribbon.
20. 16. In a type-writing machine the combination with a reciprocal carriage, and ribbon-reels supported upon and movable with said carriage, of a stationary bar rigidly mounted upon the machine-frame and carrying means 25 for intermittently actuating said reels at the end of each reciprocation of the carriage.
17. In a type-writing machine, the combination with a reciprocal carriage, and horizontally-disposed ribbon-reels supported upon 30 said carriage at opposite ends thereof and movable therewith, of a stationary bar rigidly mounted upon the frame of the machine and extending in the line of movement of the carriage, the ends thereof carrying means for 35 intermittently actuating said reels at the end of each reciprocation of the carriage.
18. In a type-writing machine, the combination with a reciprocal carriage, a cylindrical platen journaled therein, and ribbon-reels sup- 40 ported by and movable with said carriage, of
- stationary means for independently actuating said reels, a stationary frame, and reels for record-paper journaled therein and located such a distance from said platen as to permit without injury of the lateral movement of 45 the record-paper held by said platen.
19. In a type-writing machine, a stationary frame a carriage mounted to reciprocate thereon, ribbon-reels supported by and movable with said carriage, and means supported upon the stationary frame for rotatively actuating the ribbon-reels at the end of each reciprocatory movement of the carriage. 50
20. In a type-writing machine, the combination with a stationary frame, of a carriage 55 mounted for reciprocatory movement thereon, ribbon-reels supported by and movable with said carriage and disposed on opposite sides respectively of said carriage, and detachable devices mounted upon the stationary frame for rotatively actuating said reels. 60
21. In a type-writing machine, the combination with a carriage mounted to reciprocate, a platen mounted thereon to move therewith, and ribbon-reels also supported by and 65 movable with said carriage, a stationary frame for supporting record-paper to be supplied between the platen and ribbon, said stationary frame being located a sufficient distance from the reciprocatory carriage as to 70 permit the reciprocations of said carriage without injury to the record-paper.

In witness whereof I have hereunto set my hand this 16th day of May, 1904, in the presence of the subscribing witnesses.

ERNEST F. ELMBERG.
